UNITED STATES PATENT OFFICE.

SAMUEL V. WIGHT, OF TOLEDO, OHIO, ASSIGNOR TO GEORGE SACO, OF TOLEDO, OHIO.

HEATER FOR ENGINE-COOLING SYSTEMS.

1,178,433.

Specification of Letters Patent.

Patented Apr. 4, 1916.

Application filed December 16, 1913. Serial No. 807,153.

To all whom it may concern:

Be it known that I, SAMUEL V. WIGHT, a citizen of the United States, residing at Toledo, in the county of Lucas and State of Ohio, have invented new and useful Improvements in Heaters for Engine-Cooling Systems, of which the following is a specification.

This invention relates to heaters for engine cooling systems, the object of the invention being to provide a simple, economical and effective heating apparatus by means of which water contained in the circulatory cooling system of an internal combustion engine may be maintained at a suitable temperature to prevent freezing and to facilitate the starting of the engine, when said engine is out of use.

Automobiles, motor-trucks and other vehicles propelled by internal combustion engines are frequently, by necessity, left standing in exposed places in cold weather for a considerable period of time sufficient to enable the cooling water to freeze and seriously injure various parts of the engine and its equipment such as the cylinders, pump and radiator, and the aim of this invention is to overcome such liability by means of a simple apparatus applicable to any automobile, motor truck or the like which will prevent the water from freezing, thereby avoiding injury to the parts referred to and also keeping the engine, radiator and other parts warm so as to greatly facilitate the starting of the engine.

A further object of the invention is to so construct and arrange the heater that communication may be cut off between the auxiliary heating system and the ordinary water cooling system of the engine when said heating system is not in use.

With the above and other objects in view, the invention consists in the novel construction, combination and arrangement of parts, as will hereinafter be more fully described, illustrated and claimed.

In the accompanying drawings:—Figure 1 is a side elevation partly in section showing the heating apparatus of this invention in its relation to an automobile. Fig. 2 is a detail elevation of the heater. Fig. 3 is a vertical diametrical section through the heater. Fig. 4 is a fragmentary vertical section through the lower portion of the heater.

One method of applying the heating ap-

paratus of this invention is illustrated in Fig. 1 wherein 1 designates the radiator which is ordinarily located in front of the engine of the machine, 2 designating the frame of the automobile, 3 the front springs and 4 one of the front steering wheels of the machine.

The apparatus contemplated in this invention comprises a lamp or heater 5 which as shown in Fig. 3 embodies an outer casing 6 and an inner shell 7 arranged in spaced but concentric relation to each other, the inner shell 7 being surrounded by a covering of asbestos as shown at 8 to conserve the heat within the casing.

Connected to the bottom of the casing in any convenient manner is a fuel container or font 9 which supplies a burner 10 shown as of the ordinary wick form, 11 designating the wick raiser. The burner also comprises a top embodying an outer wall 12 and an inner wall 13 in spaced relation to each other so as to permit the air to enter through opening 14 in the top of the casing, the air passing downwardly between the casing 6 and shell 7 and between the base 15 and a contracted bottom portion 16 of the inner shell 7 and thence upward to supply the necessary oxygen to the flame of the burner 10. The air heated by the burner passes upwardly through the heater and escapes through the outlet orifices 17 adjacent to the top of the burner thus preventing the flame from being extinguished in windy weather.

Located within the central body portion of the heater is a water heating coil 18 preferably of frusto-conical shape as shown in Fig. 3 and forming a continuation of an inlet pipe 19 and an outlet pipe 20.

The pipe 19 may be made of any suitable length and is provided with a coupling 21 adapting it to be attached to a suitable point in the water cooling system of the engine such as the bottom of the radiator as indicated in Fig. 1. Said pipe 19 is provided adjacent to its extremity or, in other words, adjacent to the coupling 21, with a stop cock 22. The other pipe 20 is recurved as shown in Fig. 1 to extend down under the radiator, in the embodiment of the invention illustrated in Fig. 1 and thence upward where it is connected by a suitable coupling 23 to the top of the radiator and equipped adjacent to said point with a stop cock 24. The stop cocks 22 and 24 enable

the heating system of this invention to be placed in communication with or cut off from communication with the cooling system of the engine.

- 5 It is to be understood that the arrangement shown in Fig. 1 is only one embodiment of the invention. The pipe 19 will ordinarily be connected to the lowest point in the circulatory cooling system of the engine, such point to be at the bottom of the radiator or the pump or the water jackets of the cylinder. The idea is to take the water from the lowest point of said circulatory cooling system and carry it to the 10 heater of this invention and from said heater return the water into the cooling system at a relatively high point. This insures a thermo-siphon action and insures the heating of all the water in both the heating system of this invention and the ordinary water cooling system of the engine.

The heater is preferably provided at one side with an attaching lug 25 formed with a slot 26 to receive the usual supporting bracket attached to any convenient part of the machine frame as, for example, the frame 2 in Fig. 1. It will, however, be apparent that the heater may be supported on any convenient part of the machine.

- 30 When the operator leaves his car for a long period in cool weather, it is only necessary to light the burner of the heater and adjust the same to the proper height in accordance with the temperature at the time. 35 The heater gradually warms the water and induces a circulation through the pipes 19 and 20 and consequently through the circulatory water system of the engine. This prevents the water from freezing and also keeps 40 the engine warm and in condition for starting. Therefore, it is not necessary to prime the engine in order to start the same, thus saving fuel. Furthermore, the owner of the machine is relieved of worry and is relieved 45 of the expense of repairing injured parts of the automobile or other machine due to freezing and fracture of the water containing parts of the engine and its equipment.

In view of the fact that the engine is 50 kept warm by the apparatus hereinabove described, the liability of back fire through the carburetor when starting the engine in cold weather is overcome and the consequent danger of fire due thereto.

- 55 In order to provide for lighting the burner, the inner and outer walls of the casting are pierced and relatively braced adjacent to said burner by a tube 27 through which a match or other lighter may be in-

serted, the outer end of said tube being normally closed by means of a cap or shutter 28 containing a glass or other transparent panel 29 to enable a person to ascertain at a glance whether or not the burner is still ignited. The cap or closure 28 may be hinged 65 to the end of the tube 27 as indicated at 30 or otherwise mounted so that it may be opened and closed.

In order to comply with the rules of insurance companies, any lamp or burner used 70 adjacent to or upon an automobile, must be perfectly safe so that it will not ignite fumes of gasoline. By reason of the way in which the draft is arranged in the heater hereinabove described and shown in the 75 drawings, it is impossible to ignite fumes of gasoline or the like and furthermore the draft arrangement prevents mud, water and other foreign matter from getting into and accumulating within the heater so as to clog 80 and interfere with the operation thereof, it being unnecessary to use any screen for the purpose. Furthermore, by reason of the particular construction of the lamp and the relative arrangement of the parts thereof, 85 the inner and outer shells of the heater are thoroughly and effectively braced relatively to each other thereby greatly increasing the life and durability of the heater which is necessarily subjected to the almost continuous jars and vibrations of the machine upon which it is used.

What I claim is:—

A water heater for the purpose specified, comprising an outer shell embodying a cylindrical central body portion and upper and lower frusto-conical end portions, a conico-cylindrical inner shell gradually contracting in diameter upward and then extended to form a cylindrical closed top chimney 95 which passes through and closes the top of the outer shell and is formed with lateral air outlet ports above said outer shell, the latter being formed with air inlet ports adjacent to its junction with the chimney, a 100 frusto-conical water coil all of the convolutions of which lie in close proximity to the inside surface of said inner shell and the outlet portion of which extends through the closed top of the chimney, and a burner 105 detachably secured to the bottom of the outer shell.

In testimony whereof I affix my signature in presence of two witnesses.

SAMUEL V. WIGHT.
